Des. 447

James L. Jackson of New York N. Y.
Letters Patent No 447 Dated Feb 17th 1852.

The schedule referred to in these Letters Patent, and making part of the same
To all whom it may concern.

Be it known that I James L Jackson of the City, County and State of New York, have invented or produced a certain new and original design for a Grate Frame and Summer piece, and I do hereby declare the following

to be a full clear and exact description of the same reference being had to the accompanying drawings making a part thereof in which figure 1 represents the graticle frame one half of which is finished, the other in outline and showing by sections the projection of the parts enumerated. figure 2 in like manner the summer piece.

The outer margin of the frame (fig 1) is finished with a bead moulding, a which terminates in the upper corners in foliated scroll work b. so curved inward, and entwined with the top outer moulding as to slightly round off said corners. The moulding on top of the frame in the centre thereof is divided, and curves slightly upward, and terminates in volutes c, surmounted by a lozenge d, and underlaid by three leaves. From the foliated scroll work b. in the corners starts a curved stem e, which is interlocked with a fanciful foliated vine f out of which springs a flower g. the whole making a flower in Arabesque which fills up the corner of the paneling h.

From this paneling h on a base i near the foot of the jamb, rises a convex moulding highly finished with a running vine j with leaves k, and fruit l. This moulding rises perpendicularly for about two thirds of the height of the frame, and then sweeps round in a semi elliptical form until it meets the moulding on the opposite side of the frame, arranged in a precisely similar manner and is wrought with the before mentioned vine leaf and fruit. From the termination of the convex moulding rises a sharp edged plain beading m, the two sides of which, are ornamented with diamond work n. Inside of this ornamented a bead is a cavetto moulding o, which has near its inner edge a chain beaded moulding p.

The summer piece (fig 2) is made to fit the opening in the graticle frame, and has a deep, sunken, open lace work panel q, in its centre, out of which rises a shield r, with radiating arms, and open work between them. Outside of these arms is a circle of chain beaded work s, and on the slope of the shield is a scroll work t with an open ground. The lace work panel is margined by a convex moulding outside

3.

of which is foliated scroll work in the Elizabethian style with open ground work, and surrounded with a sharp gothic border which terminates in a pendant w. The lower part of the summer piece is also ornamented with lace work & flanked by foliated scroll work.

The sections A, B, fig 1, and C fig 2 represent the projections of the several parts herein enumerated.

Having thus described the nature of my design what I claim therein as new, and desire to secure by letters of patent, is the combination, and arrangement of the ornamental figures herein represented, and forming an ornamental design for a Brate Frame and summer piece.
